UNITED STATES PATENT OFFICE.

PHILIP A. JACKSON, OF DAYTON, OHIO, ASSIGNOR TO THE EGRY REGISTER COMPANY,
OF DAYTON, OHIO, A CORPORATION OF OHIO.

AUTOGRAPHIC REGISTER.

Application filed May 27, 1926. Serial No. 112,145.

My invention relates to autographic registers.

It is the object of my invention to provide an autographic register which will align paper sheets by positively moving aligning pins into the holes in the sheets and simultaneously spreading the ejecting rollers, the pins being adapted to ride on the top of the sheets until the holes in the sheets permit the descent of the pins and the spreading of the rollers so that any length of printed forms customarily employed in autographic registers may be employed without changing the mechanism.

15 It is the chief object of this invention to provide a positive means for drawing the pins into the holes in the sheets and spreading the ejecting rollers and a positive means for quickly moving the pins vertically and 20 equally quickly clamping the sheets.

In this invention it is a further object to provide an autographic register in which the sheets are held by the ejecting rollers in a clamped position during the writing operation. When the sheets written upon are being ejected the pins will ride on top of the sheets until the file punch holes appear whereupon the pins will drop in the file punch holes aligning the sheets which are 30 then in loose form because the rollers have been spread. After this aligning operation takes place by a continued movement of the actuating handle and mechanism the pins are suddenly withdrawn vertically and the sheets 35 are clamped for the next writing operation with the sheets in aligned condition, all the above operations being performed automatically upon the movement of the crank handle.

40 In the accompanying drawings:

Figure 1 is a side elevation showing the driving gear with the cover thereon removed;

Figure 2 is a section on the line 2—2 of Figure 1;

45 Figure 3 is a top plan view of the register in closed condition;

Figure 4 is a section on the line 4—4 of Figure 1 showing in detail the driving gear in plan together with a plan view of the actuating and aligning mechanism;

50 Figure 5 is a section on the line 5—5 of Figure 6;

Figure 6 is a section on the line 6—6 of

Figure 4 showing the parts in the position they would occupy when riding on top of the sheets prior to entering the holes;

Figure 7 is a similar section showing the position of the parts when the pins have entered the holes and spread the rollers;

Figure 8 is a similar view with the pins just withdrawn from the sheets after aligning them and the rollers reclamped, the parts being in the position they occupy during the writing operation.

Referring to the drawings in detail, 1 is a base plate of an autographic register having side walls 2 with a cover 3 pivoted thereon at 4. This cover is provided with a writing opening 5 through which is displayed the usual form 6 on the several sheets of superimposed paper between which interleaved carbon sheets are spaced in the usual manner. The forward end of the register is closed by a slide 7 held in place by a hinged front wall 8.

The register is provided with a driving handle 9 which is limited in its movement at each stroke by the movable stop 10 pivoted on the side wall of the register at 11. This handle 9 is mounted on an actuating shaft 12 which carries a master actuating gear 13 which in turn meshes with a pinion 14 which is fixed to a larger gear 15, both being carried on a stub shaft 16 mounted on the side wall 2 of the register.

The larger gear 15 meshes with a gear 17 mounted on the lower roller shaft 18 journaled in the side walls of the register. This lower shaft 18 is provided with an intermediate knurled driving roller 19 and spaced side supporting rollers 20. The space between the rollers is designated 21 and is adapted to receive the aligning pins 22 which are carried upon a transverse pin support designated 23. The gear 17 on the shaft 18 meshes with a gear 24 on the upper roller shaft 25 which carries a central knurled driving roller 26 and spaced therefrom on either side lateral rollers 27. A space between the rollers is provided for the movement of the pins 22 therethrough. The shaft 25 upon which these upper rollers are mounted is supported in upstanding housings 28 forming parts of the side walls of the register.

The springs 29 carried in such housings 105 yieldingly resist the upward movement of

the upper rollers and the spreading of such rollers from the lower rollers. These supports over the ends of the upper shaft 25 consist of the vertical reciprocating supporting plates 30 which move parallel to the side walls of the register and are located on the ends of the upper shaft in engagement therewith. The lower shaft 18 passes therethrough by reason of a slot formed in the plates 30.

These plates are supported at their lower ends by the actuating finger 31 pivoted at 32 on the side wall of the register and being provided at its inner end with a nose 33 which is engaged by the lever 34 pivoted on the side wall at 35. On either side of the register will be found similar parts 30, 31, 32, 33, 34 and 35. The lever 34 is provided with a notch 36 at its outer end which fits over a pin 37 carried on the vertical pin supports 38 on either side of the register which are attached to the cross support 23 supporting the pins 22. The lower end of these vertical supports 38 are provided with slots 39 in which are located guide pins 40 carried by the side walls of the register. On the lower ends of these vertical supports 38 are mounted brackets 41 connected to a spring 42, the lower end of which is connected at 43 to the bottom 1 of the register.

The vertical support 38 is provided with a rearwardly projecting shoulder 44 which is adapted to engage with the rear end 45 of a cam follower 46 which is mounted on the shaft 47.

This shaft is provided in the side walls of the register. The other end of the cam follower 46 is provided with a hooked end 48. This cam follower rides upon a cam 49 turning with the shaft 12 which is directly driven by the actuating handle 9. This cam is provided with a high portion 50 and a lower portion 51. The shaft 47 has mounted thereon a helical spring 52 connected to it at 53 and to the side wall of the register at 54. Similar cams, cam followers and overhanging shoulders 44 are provided on either side of the register.

In order to have an independent movement for spreading the rollers irrespective of the operation of the machine, there is provided a transverse shaft 55 having cam portions 56 adapted to engage with the vertical slides 30 as the shaft 55 passes through slots 57 in such plates. The horizontal surface 58 of the slot is adapted to engage with the cutaway cam face 56 of the shaft 55 when in operative position and the rollers are in engagement with one another, but upon the rotation of the shaft by the finger piece 59 the high point of the cam or the circular surface of the rod 55 engages with the flat surface 58 of the slot 57 thereby elevating the supports 30 and lifting the upper rollers to spread such rollers from the lower rollers.

This facilitates the insertion of the sheets when the machine is being adjusted and reloaded.

Method of operation.

Assuming that the parts are in the position necessary for writing, it will be found that the engaging rollers are engaging the paper and the pins are held in their uppermost position above the paper.

The spring 52 will not be under tension but the springs 42 will be under tension. The handle will be in stopped position.

When the latch 10 is moved and the handle is started the shaft 12 will rotate and the cams 49 will rotate with it. The noses 48 of the cam fingers 46 will begin to ride up the incline of the low points of the cams 49, designated 51. In doing so, the rear ends 45 of the cam fingers 46 will descend allowing the vertical support 48 for the pins 22 to descend until the pins 22 rest upon the surface of the upper sheet of the several sheets being ejected by the rollers which are engaging with the sheets. The cams 49 continue to rotate beneath the noses 48 which are riding upon the high points of the cams, designated 50.

This continues until the pins drop into the apertures in the sheets, which they are permitted to do by reason of the fact that the rear ends 45 of the fingers 46 have descended to such a point as to permit the shoulders 44 to descend under the influence of the springs 42.

As soon as the pins descend into the holes simultaneously this downward movement of the vertical supports 38 results in the movement of the levers 34 which engage with the noses 33 elevating the levers 31 which in turn push upwardly the upper roller spreading the rollers so that, when the pins enter the sheets to align them, the sheets will be released from the rollers. While this aligning operation is taking place the actuating handle 9 continues to rotate in its given cycle of operation and just before the handle comes to rest against the stop 10 the noses 48 drop off the high points of the cams into the low points 51 being impelled to do so by the spring 52. This spring being stronger than the springs 42 serves to lift the pins suddenly from the sheets of paper and simultaneously the rollers re-clamp the sheets.

Thus we have the different steps in the operation of clamping sheets with pins out of the sheets; ejecting the sheets and lowering the pins to the surface of the sheets; the dropping of the pins into the holes of the sheets when they appear beneath the pins, the pins being pulled into the holes by the springs 42, and the simultaneous spreading of the rollers; and the final ejecting of the pins from the aligned sheets and the re-clamping of the sheets at the end of the

operation to hold them in writing position.

It will be understood that I desire to comprehend within my invention such modifications as may be necessary to adapt it to varying conditions and uses.

Having thus fully described my invention, what I claim as new and desire to secure by Letters Patent, is:

1. In an autographic register having a plurality of sheets with spaced perforations therein, actuating means, aligning means, means to move said aligning means into inoperative position and to engage the actuating means with said sheets, means to render said means inoperative during a period of the operation of handling the sheets, and means to move said aligning means into engagement with the holes in said sheets when the holes pass beneath said aligning means and to simultaneously render said actuating means inoperative, and a common actuator for operating the said several means.
2. In an autographic register having a plurality of sheets with spaced perforations therein, actuating means, aligning means, means to move said aligning means into inoperative position and to engage the actuating means with said sheets, means to render said means inoperative during a period of the operation of handling the sheets, and means to move said aligning means into engagement with the holes in said sheets when the holes pass beneath said aligning means and to simultaneously render said actuating means inoperative, and means to suddenly eject said aligning means from the aligned sheets and re-engage said actuating means with the sheets, and a common actuator for operating the said several means.
3. In an autographic register having a plurality of sheets with spaced perforations therein, actuating rollers, aligning pins, yielding means tending constantly to move said pins into inoperative position and to cause said rollers to engage with said sheets, means to resist said yielding means to render it inoperative during a period of the cycle of operations of the register, a second relatively weak yielding means adapted to pull said aligning pins into engagement with the paper sheets and into the holes thereof when the sheets pass beneath said pins and to simultaneously spread the rollers as the pins enter the sheets to align them, and means to permit said first mentioned yielding means to suddenly operate to eject said pins and re-engage said rollers with said sheets.

4. In an autographic register having a plurality of sheets with spaced perforations, upper and lower ejecting rollers engaging said sheets, spaced aligning pins with transverse and vertical supports therefor, an actuating shaft, cams thereon having low points, cam fingers mounted adjacent there-

to adapted to engage therewith, yielding means adapted to cause said fingers to engage said cams, means on said vertical supports for engaging with said cam fingers at their other ends, yielding means adapted to move said supports and pins downwardly to cause said pins to enter the holes in said sheets, means moved thereby as said supports descend for elevating the upper roller to disengage said roller from said sheets.

5. In an autographic register having a plurality of sheets with spaced perforations, upper and lower ejecting rollers engaging said sheets, spaced aligning pins with transverse and vertical supports therefor, an actuating shaft, cams thereon having low points, cam fingers mounted adjacent thereto adapted to engage therewith, yielding means adapted to cause said fingers to engage said cams, means on said vertical supports for engaging with said cam fingers at their other ends, yielding means adapted to move said supports and pins downwardly to cause said pins to enter the holes in said sheets, means moved thereby as said supports descend for elevating the upper roller to disengage said roller from said sheets, said means connecting said disengaging means for the rollers and said vertical supports consisting of a lever connected to said support at one end and pivoted on the register at the other, a second lever pivoted on the register having one end engage with the disengaging means and the other engage with the first mentioned lever.

6. In an autographic register having a plurality of sheets with spaced perforations, upper and lower rollers, said rollers having spaces therebetween for pins to be inserted therethrough, pins, a transfer support therefor, vertical supports for the transverse support on either side of said register, means to guide said vertical supports, shoulders on said vertical supports engaging with cam fingers, cam fingers mounted on a transverse shaft journaled in said register, yielding means adapted to move said shaft in one direction to one of said fingers, cams mounted on the actuating shaft, an actuating shaft, said cams having a low point which communicates abruptly with the high point of the cams, means to simultaneously drive said cams and said rollers, yielding means to press the upper roller against the lower roller, shifting means adapted to elevate the upper rollers located on either side of said register, a system of levers interconnecting said vertical supports and said shifting means, whereby they move in opposite directions, and yielding means connected to said vertical supports to yieldingly pull said pins and supports downwardly and to elevate said upper roller.

7. In an autographic register having a plurality of sheets with spaced perforations,

means to eject sheets, means to align sheets, means to render the ejecting means inoperative when the aligning operation takes place, yielding means to move the aligning means into operative position and to render the ejecting means inoperative, a relatively stronger yielding means adapted to maintain said ejecting means in operative position, and aligning means in inoperative position,

and means to neutralize the effect of the relatively heavy yielding means to allow the relatively lighter means to operate, and means to allow the relatively heavy yielding means to be suddenly restored to its operative condition.
